UNITED STATES PATENT OFFICE.

WILLIAM S. BECHTOLD, OF NEWARK, NEW JERSEY.

DESIGN FOR A HAIR PIN OR COMB.

49,417.

Specification for Design.

Patented July 25, 1916.

Application filed March 20, 1916. Serial No. 85,526. Term of patent 3½ years.

To all whom it may concern:

Be it known that I, WILLIAM S. BECHTOLD, a citizen of the United States, residing at Newark, in the county of Essex and State of New Jersey, have invented a new, original, and ornamental Design for a Hair Pin or Comb, of which the following is a specification, reference being had to the accompanying drawing, forming part thereof.

The figure is an elevation of my design.

I claim:

The ornamental design for a hair pin or comb, as shown.

WILLIAM S. BECHTOLD.
